INVENTOR

Frederic Wilkes
By Archworth Martin,
Attorney.

UNITED STATES PATENT OFFICE.

FREDERIC WILKES, OF WILKINSBURG, PENNSYLVANIA.

SPLASHBOARD.

Application filed October 30, 1926. Serial No. 145,107.

My invention relates to splash boards, and particularly to a board or guard plate for preventing a person being splashed when standing at a sink.

5 One object of my invention is to provide a splash guard of more simple and effective form than those heretofore employed.

Another object of my invention is to provide a splash board having supporting 10 means which are automatically adjustable to sinks of various sizes and contours.

One form which my invention may take is shown in the accompanying drawing, wherein Fig. 1 is a transverse sectional view 15 of a portion of a sink with my splash board in position; Fig. 2 is a rear elevational view of the board of Fig. 1, viewed from the right hand side of Fig. 1; Fig. 3 is a front elevational view of the board, and Fig. 4 is a 20 view, on an enlarged scale, taken on the line IV—IV of Fig. 2.

The board or guard plate 5 is preferably of sheet metal which may be suitably enamelled. The plate 5 is provided with an upper 25 curved edge 6 that serves to stiffen the plate and to present a smooth surface to the body of the user, and which may also serve to assist in catching water which is splashed against the plate. The vertical edges are 30 rolled or beaded as indicated at 7, to stiffen the plate and permit use of material of lighter gage. The plate is also provided with a perforation 8 that permits it to be conveniently hung on a nail or hook when 35 removed from the sink.

Metal straps 9 are welded or otherwise secured to the back of the plate 5 and have eyes formed in the ends thereof, through 40 which the rods 10 extend and by which said rods are supported for rotative movement. The rods are bent at their lower ends, so that they will not become accidentally removed from the eyes. At their upper ends, the rods are bent back so that they can be 45 suspended upon the edge of a sink. These bent portions may be of any desired form, to fit sink edges of various contours.

The pivotal mounting of the rods 10 permits them to be folded flatwise against the plate 5 when the guard is not in use, as 50 shown by dotted lines in Fig. 2. The pivotal mounting of the rods 10 also permits them to be turned at an angle to the position shown in Fig. 1, to closely engage sink rims of smaller sizes than that shown in Fig. 1. 55 The rods may be of spring steel so as to yieldably grip the edge of a sink, or may be of softer metal so that they can be readily bent to fit a sink of any size.

From the foregoing, it will be seen that I 60 provide a splash guard that may be readily applied to a sink without the use of screws and similar fastening devices, and which can be folded to compact form when not in use, and there being no loose parts which may 65 become lost or misplaced.

It will be understood that a single hook may be employed, and that the hooks may be disposed for pivotal movement about axes that are non-vertical, and that they may be 70 mounted in various other positions with respect to the plate 5.

I claim as my invention:

1. A splash guard for sinks, comprising a plate, and a rod pivotally supported upon 75 one side of said plate, for movement about a vertical axis, the said rod being provided with a hook portion for engaging the rim of a sink and being disposed wholly within the boundaries of the plane of the plate. 80

2. A splash guard for sinks, comprising a plate, and a vertically-disposed sink-engaging hook disposed on one surface of the plate, to each side of the vertical center line of the plate and being disposed wholly within the boundaries of the plane of the plate, the hooks having rotative movement about vertical axes from planes at right angles thereto to a plane in parallelism therewith. 85

In testimony whereof I, the said FREDERIC WILKES, have hereunto set my hand.

FREDERIC WILKES.
